CHAIR HEAD REST
Nathan L. Gelbman, 17201 NE. 4th Ave.,
North Miami Beach, Fla. 33159
Filed Jan. 5, 1965, Ser. No. 423,440
1 Claim. (Cl. 297—400)

This invention relates to a cushioned head rest that can be attached or detached to a chair by the average person in a few seconds without the use of any tools.

An object of this invention is to provide a novel mechanical locking arrangement thereby preventing the head rest from becoming dislodged or interfering with the folding or unfolding of a chair such as the multitude of aluminum types in use today.

Another object is that due to its light weight and flexible maneuverability, the occupant of a chair so equipped at their discretion may slidably adjust the head rest portion to meet their most comfortable requirements by raising, lowering or tilting while remaining seated.

Another object is by rotating the head rest portion 90 degrees to vertical position parallel with the main body and with the flexible covering and foam padding removed it makes it possible to roll in the head rest panel to a close proximity to the main longitudinal member thereby conserving carton space for merchandising and shipping.

These objects and other advantages of this invention will be apparent to those skilled in the art upon reference to the following specification, claim and drawing, of which:

FIG. 1 is a view of a side elevation of this invention in its completed form;

FIG. 2 is an enlarged transverse view being taken substantially along line 2-2 of FIG. 1;

FIG. 4 is an exploded perspective view of part 30 shown 40

FIG. 5 is an enlarged view taken substantially on a

FIG. 6 is a view of some parts of the lower hook like

receptacle.

In the form shown in the drawing, a longitudinal body

1 with an elongated slot 28 for the reception of bolts for attaching the various components of the invention. A hook like receptacle 3 with large enough diameter to slip over the center of a top rail of a chair slidably mounted on body 1 by means of bolt 4 through hook 3 slot 28 washer 5a secured or loosened by the manipulation of thumb nut 6 for proper setting. A smaller diameter hook like receptacle 7 mounted on body 1 so as to be freely slidable by putting 46 through slot 28 laying eye of extension spring 12 over cylinder 44 being held in place by putting flat head screw 8 through countersunk hole in hook 7 secured by screwing screw 8 tightly into female thread of flanged cylinder 46, cylinder 44 being a little longer than the width of body 1 allows it to slide freely along the face of body 1. The opposite end of spring 12 is anchored at approximately the loca-

2

tion shown in FIG. 1 depending on the amount of tension and length of spring 12 being used, slipping bolt 9 through washer 11 secured at the desired location by tightening nut 10.

5 The head rest assembly 18 is affixed to body 1 by carriage type bolt 19 passed through elongated slot 20 in semi-tubular member 21 the underside 26 of head 19a being concentric with the radius of 27 passes through opening 41 of block through slot 28 of body 1, washer 10 34 compression spring 33 the ease of slidability being controlled by the amount of compression applied by the tightening or loosening the thumb nut 29 on bolt 19. In addition to the concentrical relationship of 26 to 27 the bolt 19 is prevented from turning by its square portion 19B 15 slidable fit of slot 20. The block 30 is kept in alignment with body 1 by the two guide plates 32—32 fastened to it by the screws 43. Smooth tilting of 18 is accomplished in an arc of at least 180 degrees by concave 31 being concentric with convex 21a. Telescopic adjustment 20 is provided for 18 by means 22 thumb screws 24—24 through slots 23—23 into threaded holes 25—25 alignment is accomplished by guides 22a of part 22. The rigid panel 36 is secured to 22 by fastenings 37—37, the foam padding 38 is held in place by the flexible covering 39 secured fastenings 45—45 provided for the easy 25 removal or installation of both 38 and 39 when needed for cleaning or shipping, a pair of horizontal tracks 40—40 becomes useful when the head rest 18 is rotated 90 degrees to a vertical position parallel with body 1 30 making it possible to roll in 18 to closer proximity for compactness, conserving storage space. The shuttle like means 13 of FIG. 3 when attached to the lower hook 7 by thumb screw 14 a tri-fold purpose is accomplished, first it centers the invention in relation to a chair which 35 is constructed by using an odd number of longitudinal flexible webs, the twin finger-like projections 16—16 straddle a center web, secondly it completes the encirclement of the lower portion of a chair so that the device cannot become dislodged when folding, unfolding or jogging in 40 any manner, the third purpose it fulfills is that if a chair is constructed of an even number of webs such as four or six, all that is required to do in order to center the device is to loosen screw 14 reverse shuttle 13 180 degrees so that the single finger-like projection 17 now encircles 45 rod 49 and is at the center line of the chair between two webs, and retighten screw 14 again.

Again it will be noted that substantially on all folding chairs that the distance between the top tubular rail and the bottom rod which forms the nucleus for supporting the back webs shortens as a chair is folded due to the folding of the linkages, the variation in distance is compensated for in the invention by the contraction and expansion of spring 12.

Having illustrated and described a preferred embodiment of my invention, it should be apparent to those skilled in the art that the invention permits of modification in arrangement and detail. I claim as my invention all such modifications as come within the true spirit and scope of the appended claim.

60 I claim:

60 A main body member on which is mounted a self adjustable head rest, an upper movable hook-like recep-

tacle, a slidable lower opposing hook-like receptacle, limited in its travel by means of an extension spring attached thereto, the opposite end of which is anchored to the main body by means of a fastener which can be shifted vertically, to obtain the proper tension in order to keep the device taut when it is clamped on the back of a chair, especially the folding type where the distance between the top and bottom rail of the back varies due to the folding of the linkage, with the folding and unfolding of the chair; a shuttle fastened to the lower hook-like receptacle by means of a thumb screw or bolt and nut, having twin finger-like projections on one edge spaced apart a little greater than the width of a flexible web, a single finger-like projection on the center line of the opposite edge, an elongated slot which allows for adjusting said shuttle to encircle the bottom rod or rail.
